CLAIM

The ornamental design for a wearable robot, as shown and described.

DESCRIPTION

FIG. 1 is a front perspective view of a wearable robot showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof; and,

FIG. 9 is an enlarged view of the portion 9 delineated in FIG.

1.

The dashed broken lines in the figures illustrate portions of the wearable robot that form no part of the claimed design. The dot-dash broken lines in the figures delineating portions of the claimed design that are illustrated in enlargements form no part of the claimed design.

1 Claim, 9 Drawing Sheets

Related U.S. Application Data

a continuation of application No. 29/889,791, filed on Apr. 17, 2023, now Pat. No. Des. 1,059,607.
